CHAIR

Arthur C. Ferro, St. Louis, Mo., assignor to Contour
Chair-Lounge Co., Inc., St. Louis, Mo., a corporation of Missouri

Filed Aug. 28, 1963, Ser. No. 76,377

Term of patent 14 years

(Cl. D15—11)

The dominant features of my new design reside in the combination of the solid arm rests having rolled tops and arcuate lower edges terminating at the arcuate base in association with the configured chair, all as shown.

I claim:

The ornamental design for a chair, as shown and described.
